UNITED STATES PATENT OFFICE.

RAY L. CARTER, OF SYRACUSE, NEW YORK.

SANDING-MACHINE.

1,277,377.

Specification of Letters Patent. Patented Sept. 3, 1918.

Application filed March 25, 1918. Serial No. 234,548.

To all whom it may concern:

Be it known that I, RAY L. CARTER, a citizen of the United States, residing at Syracuse, in the county of Onondaga and State of New York, have invented certain new and useful Improvements in Sanding-Machines, of which the following is a specification.

This invention relates to improvements in sanding machines, designed particularly for use by pattern-makers, wood-workers, and the like, for grinding and finishing surfaces not accessible to the usual disk sanders in common use.

The object of the invention is to provide a novel, simple, convenient and compact sanding device of the oscillating spindle type, which is capable of being operated at high speed by a direct drive and which is light and durable, and wherein a comparatively small number of parts are employed for the operating mechanism. A further object is to provide novel and simple means for effecting the oscillation of the spindle. And a further object is to generally improve, simplify and cheapen the construction and operation of sanders of the class.

I attain these objects by the means set forth in the detailed description which follows, and as illustrated by the accompanying drawings, in which—

Figure 1 is a side elevation of the complete machine, with parts broken away; showing certain details of construction.

Fig. 2 is a horizontal section, taken on line 2—2 of Fig. 1; showing the principal parts employed for oscillating the spindle.

Fig. 3 is a broken central vertical section, taken substantially on line 3—3 of Fig. 2; showing the spindle and the oscillating mechanism.

Fig. 4 is a transverse vertical section, taken on line 4—4 of Fig. 2.

In the drawing, 2 represents the main upright body or hollow column, which is preferably mounted on a base 3. 4 represents a forwardly projecting detachable hollow body portion secured to the top front side of the column 2, by bolts 5. The part 4 has a rear side opening for access to the hollow interior which is closed by a plate or door 4'. 6 represents a tilting table which supports the work to be sanded, and which is pivotally mounted upon the top of the body 4. The table 6 is preferably made of metal, and has a depending web portion 7, the lower

margin of which comprises an inverted arc-shaped rack 8, the said web also having a corresponding arc-shaped slot 9, by which the table is guided when tilted or rotated vertically. 10 represents a threaded stud or bolt carried by the body 4, which passes through the slot 9 and cooperates with said slot for guiding the table. 11 represents a nut which screws on to the stud 10, and is operated by a handle 11', for locking the table in the various adjusted positions, as indicated by the full and dotted lines in Fig. 1. The table 6 has an oval opening 12 in its center, to receive the vertically disposed spindle, which extends some distance above the top surface of the table. The portion of the spindle projecting above the table is preferably covered with a layer of heavy sand-paper, or other suitable abradant 13', in the usual manner. The spindle 13 extends downwardly through the body portion 4, and first passes through a cap 14, which is screwed into the open top of the body 4, and directly beneath the said cap 14 there is a sleeve 15 mounted on the spindle 13, the said spindle being movable vertically in said sleeve, for oscillating the spindle-sander 13', by means of a feather or key 16, which also serves to drive the said sleeve. The upper end of the sleeve 15 is rigid in a ring 17, which is a part of a ball-bearing, consisting of rings 17 and 18 and a series of balls 19. The ball-bearing parts preferably rest upon a horizontal ledge 20 of the body 4, and are held in place by the cap 14, which holds the larger ring 18 stationary. The lower end of the sleeve 15 comprises a worm 21, which meshes a worm-gear 22, the latter being rigid by a key 22' on a shaft 23 journaled by means of ball-bearings 24—24', which are suitably supported in the body 4, as at 25—25'. The main spindle 13 extends downwardly beyond the worm 21 and its lower end is inserted and slidable endwise in a sleeve-coupling 26, which is journaled by means of a ball-bearing designated generally by the numeral 28, the latter being disposed in the lower leg of the body portion 4, between a ledge 29 and a screw-cap 30. The coupling 26 drives the spindle 13 by means of a feather or key 26'. 31 represents an electric motor of conventional form, which is mounted on the upright column 2 and is held in place by a bracket 32 and bolts 32'. The armature shaft 31' of the motor is also in-

serted in the sleeve 26 and rotates said sleeve by means of the key 26'. 34 represents the usual electric switch for controlling the motor, which is mounted on the body 2, and 5 wires 35—35' connect the motor to the switch, while wires 36—36' supply the current to the switch. The table 6 is tilted or moved into the different positions indicated by the full and dotted lines in Fig. 1, by 10 means of a pinion 37 journaled on a pin 37', and a hand-wheel 38 is employed for manipulating said pinion.

The spindle 13 which carries the cylindrical sander 13' is oscillated vertically, while 15 being rotated by the power of the motor, by a rocking lever 39, which is disposed beneath and substantially at right angles to the worm 21 and the shaft 23. One end of the lever 39 extends into the body 2 and is 20 provided with a yoke 40 which straddles flattened portions 41' of a shaft 41, the said shaft being rockable in bearings 42 in the body 2. About midway between its ends lever 39 is pivoted by a pin 43 to the lower 25 end of a link or part 44, the upper end of said link comprising a loop 44', in which is disposed a ball-bearing consisting of a ring 45 rigid in said loop, balls 45', and a smaller concentric ring 46 which is rigid on an eccentric cam 23' of shaft 23, as best seen in 30 Fig. 3. By this construction and arrangement the link 44 is given a vertically oscillating motion, which lifts and depresses the lever 39 once every revolution of the shaft 35 23. The opposite end of the lever 39 comprises a large yoke 47, which straddles the spindle 13 and is pivoted to a circular bearing-holder 48, by pivot screws 48' (see Fig. 2). The holder 48 has a circular cavity or 40 socket in its top side, in which is disposed a ball-bearing, consisting of a member 50, which is rigid in the holder, balls 50', and a smaller concentric member 51 which is rigid on the spindle 13 and movable there- 45 with. The spindle 13 has a shoulder 52 which engages the top of the member 51, and a reduced portion of the spindle continues downwardly through the holder 48 and a collar 53, the latter being disposed directly 50 beneath the holder. A pin 54 secures the collar 53 to the spindle. By this construction and arrangement, the upward movement of the rocking lever 39 lifts the spindle, while the downward movement of said 55 lever depresses the spindle. In Fig. 3, the rocking lever 39 is shown in the central position by the full lines, while the dotted lines *a—b* indicate the up and down movements

of the lever for reciprocating or oscillating the spindle 13, as well as the sander 13'. 60 The full and dotted lines at the top of Figs. 1 and 3 show the extent the sander 13' may be oscillated while performing its grinding or polishing work, by the rocking lever 39. When the lever 39 is rocked up and down, 65 as described, the end 40 of said lever slides on the flattened portion 41' of said shaft 41. This provision is necessary in order to allow the opposite end of lever 39 to move with the spindle 13 to the extremes of its strokes 70 indicated by the dotted lines *a—b*.

In practice the motor is preferably operated at about 1800 revolutions per minute, and being connected directly with the spindle and sander, the latter rotate at the same 75 speed. At the same time, the reciprocations of the spindle, owing to the reduction effected by the worm-and-gear mechanism, number from 50 to 100 revolution per minute, according to the pitch and size of the 80 worm-gear.

Having thus described my invention, what I claim as new and desire to secure by Letters Patent, is—

1. The combination with a source of 85 power, of a spindle supporting a cylindrical sander, a worm and gear driven by said spindle, said spindle slideable in said worm for oscillating said sander, a rocking lever for reciprocating said spindle, and means for 90 operatively connecting said lever with said gear.

2. In an oscillating spindle sander, a rotatable spindle, a sleeve in which said spindle is reciprocatable driven by said spindle, said sleeve comprising a worm, a rocking lever for reciprocating said spindle, a gear driven by said worm, a cam-shaft supporting and operated by said gear, and means for operatively connecting said cam-shaft with said 100 rocking lever.

3. In a sanding machine, a spindle supporting a cylindrical sander, a sleeve for driving said spindle, a second sleeve surrounding and driven by said spindle, said second sleeve comprising a worm, a worm-gear driven by said worm, a shaft supporting and driven by said gear, said shaft having a cam, a link engaged and operated by said cam, and a lever rocked by said link, 105 one end of said lever connected to said spindle adapted to reciprocate said spindle in said sleeves.

In testimony whereof I affix my signature.

RAY L. CARTER.
